(57) **CLAIM**

The ornamental design for a steering wheel for autonomous car, as shown and described.

DESCRIPTION

FIG. 1 is a front perspective view of a steering wheel for autonomous car, according to the present invention.

FIG. 2 is a front view thereof.

FIG. 3 is a rear view thereof.

FIG. 4 is a left side view thereof.

FIG. 5 is a right side view thereof.

FIG. 6 is a top plan view thereof; and,

FIG. 7 is a bottom view thereof.

The broken lines depict portions of the steering wheel that form no part of the claimed design.
